UNITED STATES PATENT OFFICE.

FERDINAND D. PIFER AND EUGENE SORRELLS, OF HOT SPRINGS, ARKANSAS.

RAILWAY-TIE.

1,101,328.

Specification of Letters Patent. Patented June 23, 1914.

Application filed February 6, 1914. Serial No. 817,082.

To all whom it may concern:

Be it known that we, the undersigned, FERDINAND D. PIFER and EUGENE SORRELLS, citizens of the United States, residing at 5 Hot Springs, in the county of Garland and State of Arkansas, have invented certain new and useful Improvements in Railway-Ties; and we do hereby declare the following to be a full, clear, and exact description 10 of the invention, such as will enable others skilled in the art to which it appertains to make and use the same.

This invention relates to a railway tie and embodies an improvement in a composite structure therefor.

An object of this invention is to couple and clamp opposite rails.

Another object is to retain said rails from spreading.

20 Another object is to allow of a device wherein said tie can be reversed and yet used as freely as theretofore.

In our invention like reference characters refer to like parts throughout, in which,

25 Figure 1 is a portion of our invention assembled in operative position. Fig. 2 a sectional elevation thereof in assembled position, and, Fig. 3 is a sectional view of our invention.

30 Our device is composed of a hollow base 1 having an approximately elliptical bore 2 therethrough having at the upper surface thereof a grooved recess 3 having beveled sides 4 and 5 respectively. Apertures 7 extend upward from this recess. At the ends of said tie I have struck up flanges 8 and 9, their inner surfaces 10 and 11 of which are beveled to conform to the surface of an ordinary rail base. Through each of said flanges 35 are transverse apertures 12. Intermediate of said flanges are two raised tongues 13 having beveled sides 14. A pair of rails 15 and 16 is respectively mounted on said tie against the inner surfaces 10 and 11 of said

40 flanges as shown. Between said rails and upon said tie, we place a clamping member 17, said clamping member having beveled grooves 18 therein to match the beveled surfaces of said raised tongues 13, and said

50 clamping member having beveled surfaces 19 and 20 respectively to match the inner surfaces of ordinary railway rails, said clamping member also having vertical apertures 21 therethrough registering with the 55 apertures 7 in said tie. Said clamping

member has also transverse apertures therethrough 22 and 23. Said clamping member is adjusted into position on said tie by a sidewise movement and locked into position against transverse play by means of 60 bolts 24 the heads of which are placed in said recesses 3 of said tie and locked in position by means of nuts 25 and threaded onto the end thereof. The corners of said clamping member are recessed as at 26 for 65 the insertion of tie plates 27 which are locked into position by means of transverse bolts 28 placed through said apertures 22 and 23 respectively. Like recesses 29 are made in the edges of said flanges and tie 70 plates 30 are set therein and locked into position by means of transverse bolts 31 as shown, said tie plates 27 and 30 being locked to said rails by bolts 32 in the ordinary manner. This arrangement allows of the 75 surfaces of said tie plates being flush with the surfaces of said tie and clamping member, said recesses acting as a seat thereto against play or displacement of said tie plates.

80 It is our intention to place a tie such as of our construction at each end of a pair of the ordinary 32 foot rails and one at the center thereof, thus making them approximately 16 feet apart and filling the intermediate spaces with the ordinary common tie. Thus we have a device that is comparatively simple and cheap in structure, one that will rigidly clamp said rails in position, one that will not allow said rails to 85 spread or turn over, one that can readily be reinforced by extra devices if necessary through said bore 2, one wherein the locking bolts 24 will be retained in an approximately central position by the head of said 90 bolts playing on the beveled surfaces 4 and 5 of said recess 3. Again our device can be reversed and used as in its original state in case of excessive wear on one end.

95 We claim:

1. A tie composed of a base member, a bore through said base member, a recess in said bore, raised tongues on said base member, a clamping member slid onto said raised tongues, locking bolts locking said clamping member to said base member and tie plates clamping said device to a pair of railway rails.

105 2. A tie composed of a hollow base member having beveled tongues thereupon, bev-

100

105

110

beveled end flanges thereto, a rail clamp having beveled recesses therein mounted upon said tie member, apertures therethrough, and devices for locking said members together and 5 to ordinary rails.

3. A tie composed of a base member, having raised portions therein, a beveled groove recessed through said base member, vertical apertures leading from said groove, beveled 10 flanges on said base member, recesses in the edges of said beveled flanges, transverse apertures through said flanges connecting said recesses, and a clamping member having beveled grooves therein to match said 15 raised portions of said base member, vertical apertures therein registering with vertical apertures in said base member, recesses at the edges of said clamping member, transverse apertures connecting said recesses, tie 20 plates seated in said recesses of said base member and said clamping member, transverse bolts locking said tie plates and bolts mounted through said registering vertical

apertures locking said clamping member to 25 said base member.

4. A tie composed of a clamping member having oppositely disposed beveled faces to match the faces of an ordinary rail, a base member under said clamping member, having end flanges thereto with beveled surfaces 30 to match the surfaces of an ordinary rail, a plurality of longitudinal locking devices, a plurality of transverse locking devices and a plurality of tie plates clamped thereto, said tie plates being seated in recesses therefor 35 so that said tie plates are flush with the surfaces of said devices.

In testimony whereof we have signed our names to this specification in the presence of two subscribing witnesses.

FERDINAND D. PIFER.
EUGENE SORRELLS.
